(57) **CLAIM**

The ornamental design of a grater, as shown and described.

DESCRIPTION

FIG. 1 is a perspective view of a grater showing my new design;

FIG. 2 is a front view of the grater;

FIG. 3 is a right side view of the grater, the left side view being a mirror image;

FIG. 4 is a back view of the grater;

FIG. 5 is a top view of the grater; and,

FIG. 6 is a bottom view of the grater.

Broken lines shown in the FIGS. are for illustrative purposes and form no part of the claimed design.
